UNITED STATES PATENT OFFICE.

ORVILLE L. PARMENTER, OF RACINE, WISCONSIN, ASSIGNOR TO RACINE PAPER GOODS COMPANY, OF RACINE, WISCONSIN, A CORPORATION OF WISCONSIN.

PACKING-STRIP FOR CIGARS AND OTHER ARTICLES.

1,249,184.

Specification of Letters Patent.

Patented Dec. 4, 1917.

Application filed April 19, 1917. Serial No. 163,103.

To all whom it may concern:

Be it known that I, ORVILLE L. PARMENTER, a citizen of the United States, and resident of Racine, county of Racine and State 5 of Wisconsin, have invented certain new and useful Improvements in and Relating to Packing-Strips for Cigars and other Articles, of which the following is a specification.

- 10 This invention relates to certain improvements in packing strips for cigars and other articles; and the objects and nature of the invention will be readily understood by those skilled in the art in the light of the following explanation of the accompanying drawings illustrating what I now believe to be the preferred mechanical expression or embodiment of the invention from among other forms within the spirit and scope thereof.
- 15 20 The object of the invention is to provide certain improvements in packing strips and the like composed of series of flexibly connected collapsible or expansible cells.

The invention consists in certain novel 25 features in construction and in combinations and arrangements as more fully and particularly set forth and specified hereinafter.

My present invention is characterized, in 30 whole or in part, by collapsible cells, each composed of a flexible folded sheet, flexibly hinged or connected together to form a strip by securing an end or edge portion of the sheet of a cell to the wall of the next cell.

35 Referring to the accompanying drawings: Figure 1 is a perspective view of a portion of a strip showing several of the connected cells thereof expanded.

Fig. 2 is a detail perspective view of one 40 of the individually complete cells detached from the strip.

Fig. 3 is a section on the line 3—3, Fig. 1.

Fig. 4 shows the sheet forming a cell, detached and flattened out.

45 In the particular embodiment illustrated, each cell is composed of an approximately rectangular sheet 1 of suitable flexible material (such as paper or any other sheet material possessing the required characteristics) suitably folded to bring its end or edge portions together which edge portions are secured together to form an individually complete open end tube, although I do not wish to limit all features of my invention to

cells or tubes, each of which is open at both 55 ends.

This sheet 1 is folded on the spaced parallel longitudinal fold lines *a*, *a*, to provide the central panel 2 forming the closed side wall of the cell and to provide the opposite 60 overlapping end portions or panels 3, 4, forming the opposite or multiply side wall of the cell and preferably secured together, as by adhesive 8. The outermost of these two overlapping sheet portions 4 has its edge portion free 65 or extended to form a connecting or hinge flap or edge portion 5 by which the cell is flexibly secured to the next adjacent cell in the formation of the strip by suitable means such as adhesive 7. The innermost or underlying panel 3 of the multiply side wall of the cell extends approximately throughout the full width of said wall and the outer surface of the end or edge portion 6 thereof is secured to the inner surface of the outer 75 panel 4, by the longitudinal stripe of adhesive 8 so as to leave the flap 5, free and disconnected from the adjacent outer surface of panel 3.

The cells are united to form the completed 80 strip through the medium of adhesive material 7 (or other securing means) securing the outer surfaces of flaps 5 of the cells to the outer surfaces of the single ply walls 2 of the adjacent cells to one side of the longitudinal center lines of walls 2. In the completed strip, the cells are preferably similar and parallel with their single ply walls 2 85 all facing in the same direction and with their multiply walls arranged beside the single ply walls of the adjacent cells and united thereto by the flaps 5 which constitute flexible or hinge connections between the cells and on which the strip can flex or bend in either direction when being rolled into a coil 90 for insertion into a statutory container for cigars, after each cell has been supplied with a cigar and thereby expanded. However, the cells can receive and hold other articles than cigars, and can be used for containing 100 and packing various articles in boxes or other containers.

If so desired, the adhesive 7 for uniting the cells, can be applied in a comparatively narrow stripe on and longitudinally of the 105 outer surface of panel 3 of each cell and hence secure the single ply wall 2 of each cell to the flap 5 of the adjacent cell, or in

the process of manufacture, a continuous tube can be produced, such as described, with the overlapping panels united by adhesive 8, and a stripe of adhesive can be applied to the outer surface of the single ply wall 2, to one side of the longitudinal center thereof or to the flaps 5, and this tube can be then wound or coiled on itself under pressure to form convolutions wherein the multiply wall overlaps the single ply wall with the stripe of adhesive engaging only the flap 5 and the half portions of panel 2. The coil of adhering overlying convolutions can then be cut into lengths to form strips of cells of the desired length as shown expanded by Fig. 1. These strips can be expanded to open the cells, as shown, or can be compressed to collapse or close the cells, for packing and shipment.

If so desired, the edges of the sheets at the ends of the cells can be slit, notched or otherwise formed, to prevent injury to the wrappers of cigars when being inserted in the cells.

It is evident that various changes and modifications might be resorted to without departing from the spirit and scope of my invention and hence I do not wish to limit myself to the exact disclosure hereof.

What I claim is:—

1. A flexible packing strip composed of a series of united collapsible cells, each composed of a single folded flexible sheet secured together at its opposite edge portions to provide a single connecting flap which is secured to the side wall of the next cell of the series.

2. An expandible packing strip composed of a series of united collapsible parallel individually-complete cells, each cell consisting of a flexible sheet folded with its edge portions overlapping and one projecting to form a connecting flap, the connecting flap of each cell secured to the adjacent wall of the next cell of the series.

3. A packing strip composed of a series of united expandible cells, each cell consisting of a flexible sheet folded to form a single ply side wall and an opposite multiply side wall, the outer ply of said last mentioned wall forming a connecting flap, said flaps of the cells being united to the next cells in the series.

4. A packing strip composed of a series of united expandible cells, each cell composed of a flexible sheet folded on itself with its ends overlapping to form a single ply side wall and a multiply side wall, the end of the outer ply of said last mentioned wall forming a flexible connecting flap, said flaps of the cells being secured to the adjacent single ply walls of the next cells of the series, the end of the inner ply of each multiply wall being secured to the outer ply.

5. An expandible packing strip composed of a plurality of flexible sheets, one end of each sheet secured to an intermediate portion of the next sheet to one side of the center longitudinal line of the sheet, each sheet being folded to form a flat cell with the other end of the sheet forming an inner ply behind said secured end.

ORVILLE L. PARMENTER.
